UNITED STATES PATENT OFFICE.

HAROLD RAYMOND WARREN, OF BOSTON, MASSACHUSETTS, ASSIGNOR TO P. R. WARREN COMPANY, OF BOSTON, MASSACHUSETTS, A CORPORATION OF MASSACHUSETTS.

PAPER BOX.

Application filed April 23, 1919. Serial No. 282,000.

To all whom it may concern:

Be it known that I, HAROLD RAYMOND WARREN, a citizen of the United States, residing at Boston, county of Suffolk, State of Massachusetts, have invented a certain new and useful Improvement in Paper Boxes, of which the following is a specification, reference being had therein to the accompanying drawings.

10 My invention relates to paper boxes of the type ordinarily known as knockdown boxes, and which are made from a sheet of box board of suitable shape creased and folded to form the box, the parts thereof being held together by the folding and by suitable tucks. One object of my invention is to provide a stronger box of this type, another object is to provide a box of this type which shall have a display surface extending upwardly from one end of the box when open and means to support the box in an inclined position, the whole being formed from a single blank. The box is intended to be enclosed within a so-called tube for shipment. The tube is removed before the goods are displayed, and the display surface is bent up into a vertical position. The support is also erected and the free end is secured to the bottom of the box. The support is provided with a reinforce which helps to resist the weight of the goods in the box, and also makes the box more durable if subjected to rough handling.

An important advantage of the box embodying my invention is that it can be made from single coated stock and all the printing is on one side of the blank, so that the expense of printing the second side is avoided. Another important advantage of the box is that it can be shipped flat, or with the blank in flat condition, but partially folded upon itself. The box can be set up when required with much less effort than has heretofore been required to set up boxes of this general character.

The invention will be fully understood from the following description when taken in connection with the accompanying drawings, and the novel features thereof will be pointed out and clearly defined in the claims at the close of this specification.

Fig. 1 is a plan view of a blank from which a box embodying my invention may be made.

Fig. 2 is a top plan view of the box partially set up. 55

Fig. 3 is a longitudinal vertical section of a completed box.

Fig. 4 is a bottom plan view of the box shown in Fig. 3. 60

Fig. 5 is a plan view of the box blank folded for shipment.

Fig. 6 is a section on line 6—6 of Fig. 2.

Fig. 7 is a section on line 7—7 of Fig. 5.

Referring now to Fig. 1, there is shown in this figure the blank from which the box is formed. This blank is made from suitable box board coated on one side only, and is divided into suitable areas by creasing, scoring, wetting or in any other suitable manner. The entire visible outer surface of the box when set up is free from tucks, creases or slots and is therefore available for printed matter.

In Fig. 1, the creases are indicated by dash lines. The blank includes an inner bottom 11, a bottom 12 and a display surface 13. Adjacent the bottom 12 are two outer sides 14—14 and two inner sides 15—15. The left-hand inner side 15 is provided with a glue flap 16 for a purpose which will be later explained. An inner end 17 is secured to the short edge of the inner bottom 11 and to the display surface 13, while the outer end 18 is secured to the left-hand outer side 14. This outer end 18 is provided with an end tuck 19. The other end of the box is formed by the superposition of an outer end 20, an inner end 21 and a holding flap 22. These are secured to that edge of the bottom 12, which is at the bottom of Fig. 1. To the edge of the bottom 12, which is at the top of Fig. 1, is secured a vertical support 23 and two bottom support pieces 24 and 25. The bottom support piece 25 is provided with a tuck 26, creased as shown at 27—27. From the bottom 12, there is died out a reinforce 28. The outer sides 14—14 are provided with tucks 30 and 31, and the inner sides 15—15 are provided with members 32 and 33 respectively, which are conveniently referred to as tucks although they do not perform the functions ordinarily performed by tucks.

In making up the box, the blank is first folded along the lines *a* and *b* to superpose the inner sides 15 on the outer sides 14. This also superposes the inner bottom 11 on

the bottom 12. The glue flap 16 lies between the two bottoms 11 and 12 and serves to hold the inner side 15, to which it is attached, close against the outer side 14. If preferred, the glue flap 16 may be secured by glue to the under side of the inner bottom 11. Ordinarily this is not necessary. The sides of the box are then turned up into a vertical position and the tucks 32 and 33 are turned in 10 as shown in Fig. 2. The inner end 17 with the display surface 13 attached is then turned up into a vertical position and lies in contact with the tucks 32 and 33. The outer end 18 is then folded over onto the inner end 17, and the end tuck 19 is inserted between the inner and outer sides 14 and 15 respectively. It will be seen that when this has been done the display surface 13 naturally stands erect and the inner end 17 is 20 prevented by the two tucks 32 and 33 from bending down into the interior of the box. The other end of the box may be made in any convenient manner. It may be constructed like the first described end or it 25 may be formed by turning in the tucks 30 and 31 and folding over them the outer end 20 and the inner end 21. These parts are held in place by the frictional contact between the holding flap 22 and the interior 30 of the box. The portions of the blank which form the support are then folded into a position adjacent the bottom 12, and the tuck 26 is inserted in the slot *c* in the bottom 12. This holds the supporting parts in a convenient 35 position and the box is now ready to receive the goods. After receiving the goods the display surface 13 is folded down over the goods and the box may be slipped into a tube not shown according to the circumstances of use.

When the goods are to be displayed on the counter, the box is removed from the tube and the tuck 26 withdrawn from the slot *c*. The reinforce 28 is then bent in a position 45 adjacent the end, its lower edge being slipped under a tuck 34. The tuck 26 is then inserted through a slot *d* in the bottom of the box. This tuck is of such shape as to resist withdrawal from the slot. The parts are 50 then in the position shown in Fig. 3, the support 23 and the reinforce 28 are in a position about parallel with the end of the box, the bottom support piece 24 is in a horizontal position and rests on the counter or shelf 55 while the other member 25 holds these parts in their predetermined position. Since the tuck 26 cannot be withdrawn from slot *d* the support cannot spread, that is cannot bend, into a horizontal position and let the 60 box down. The reinforce 28 materially strengthens the support so that the box is capable of sustaining whatever weight is imposed upon it by the goods.

The herein described box costs about one-half as much to manufacture as boxes here-

tofore constructed and provided with easels or supports by means of which the goods may be displayed with the box in an inclined position. It is therefore particularly adapted to contain and display for sale inexpensive 70 articles, such as candy, chewing gum, novelties and the like.

What I claim is—

1. The improved knockdown box formed from a single blank of material with an 75 outer bottom, inner and outer sides, an inner bottom, an inner end secured to one end of the inner bottom, tucks secured to said inner sides, an outer end and tuck secured to said outer side, and a display surface secured 80 to the inner end, said inner end projecting upwardly between the outer end and said tucks.

2. The improved knockdown box formed from a single blank of material with a 85 double bottom, an inner end secured to one of the thicknesses of said double bottom, a support secured to the edge of the double bottom and bent downwardly beneath the box to form an easel, and a reinforcement cut 90 from within the area of the double bottom and secured in position adjacent said downwardly projecting support.

3. The improved knockdown box formed from a single blank of material with a 95 double bottom and double side walls, an outer end secured to one of the thicknesses of said side walls provided with a tuck capable of insertion between the thicknesses of the other side wall, a second end secured to 100 one of the thicknesses of the double bottom, a display surface on said second end surface and tucks on one of the thicknesses of the opposite side walls, said second end surface extending upwardly between the outer end 105 surface and said tucks.

4. The improved knockdown box formed from a single blank of material with a double bottom and double side walls, a display surface secured to the inner thickness 110 of said double bottom, an easel secured to the outer thickness of said double bottom, an end secured to one of the said side walls and provided with a tuck capable of insertion between the thicknesses of the other side wall, 115 and a pair of oppositely disposed tucks secured to the inner thickness of said side walls to maintain said display surface in upright position.

5. The improved knockdown box formed 120 from a single blank of material with a double bottom and double side walls, an end secured to one of the thicknesses of said double bottom, a display surface secured to said end, means secured to said side surfaces to hold the said end and attached display surface in substantially vertical position and an easel secured to the other thickness of the double bottom.

6. The improved knockdown box formed 125

from a single blank of material with a double bottom and double side walls, an end secured to one of the thicknesses of said double bottom, a display surface secured to inner end member, and means secured to 25 said inner side members to hold the said inner end and attached display member in upright position.

5 said end, and tucks secured to one end of each of the inner side wall members which is adapted to be tucked in against the inner face of the inner end member which is attached to the display surface to hold the said 10 end and attached display surface in upright position.

7. The improved knockdown box formed from a single blank of material with a double bottom and double side walls, said 15 two outer side walls being secured respectively to the two opposite side edges of the outer bottom and the two inner side walls being secured respectively to the outer side edges of said outer side walls, the inner bottom being secured to the outer edge of one of said inner side walls, an inner end secured at one edge to one end of said inner bottom member, a display member secured 20 to the opposite end of said inner end member, means secured to said inner side members to hold the said inner end and attached display member in upright position and an easel secured to the lower bottom member. 45

In testimony whereof I affix my signature.

HAROLD RAYMOND WARREN.
